UNITED STATES PATENT OFFICE.

ALFRED JAMES JOHNSEN, OF ILOVO RIVER, AND HENRY E. JOHNSEN, OF DURBAN,
NATAL, SOUTH AFRICA.

FISH-JOINT.

1,227,271.

Specification of Letters Patent. Patented May 22, 1917.

Application filed June 30, 1916. Serial No. 106,951.

To all whom it may concern:

Be it known that we, ALFRED JAMES JOHNSEN, of Illovo River, Natal, Union of South Africa, and HENRY ENGBRETH JOHNSEN, of 136 Venice road, Durban, Natal, aforesaid, both subjects of the King of Great Britain, have invented certain new and useful Improvements in Fish-Joints, of which the following is a specification.

10 This invention relates to joints for railway rails and the like, and it comprises an improved joint of the fishplate type where-in projections on the fishplate pass through slots in the rail webs and are locked on the 15 far side thereof by a longitudinally movable member. The invention is applicable not only to fishplates for rails but also to fishplates used in joining girders of similar section to that of rails.

20 According to this invention the projections on the fishplate which pass through slots in the rail webs of both rails to be joined, are substantial projections adapted to rest on the bases of the rails at the far 25 side, and are locked by a single tapering key or bar which engages only between inclined surfaces at the top of the projections and the underside of the heads of both rails. The fishplate then has to engage only at three

30 principal points as seen in section, viz. the rail base and the rail head on the one side, and the rail base on the other side of the rail section, while the tapering key serves to press the fishplate and its projections into 35 engagement at all these points, by directly pressing the projections down upon the rail bases, and at the same time drawing up the fishplate toward the rail webs with a wedging action, so that on the insertion side it 40 will be fully in contact with the rail bases and rail heads. Hence, a tight and substantial joint is made, and if it required to be tightened after wearing for any length of time, the tightening can be effected by 45 driving in the tapering key a little farther.

The fishplate may be extended upwardly in a known manner so as to assist in carrying the wheels of trains over the joint between the rails. The construction for a girder 50 joint is identical in principle with that for a rail joint, as will be apparent but no up-

ward extension of the fishplate at the joint is required.

In the accompanying drawings:

Figure 1 is a side elevation of a joint between two rails; 55

Fig. 2 shows a cross section on the line A—B of Fig. 1;

Fig. 3 shows an end view of the joint, with the rail only in section, showing a 60 wheel passing over the center of the joint;

Fig. 4 is a side elevation similar to Fig. 1, showing a girder joint; and

Fig. 5 shows a cross-section thereof on the line C—D. 65

Referring first to Figs. 1, 2 and 3, the rails shown are of a usual form, with a head portion *a* and a foot portion *b*, and a web *c* between the same. The fishplate may be made as a forging, and has a portion *d* intended 70 to lie at the outside of the rail. The portion *d* of the fishplate may be of any suitable form, the form shown being similar to one which is already known in connection with rail joints having projections passing 75 through rail webs; that is to say the forging has an upward extension *e* which lies above the rail joint at the gap between the rail ends, and is intended to carry the wheels *f* over the joint, as indicated in Fig. 3. It 80 is optional whether or not this feature is adopted, and in any case it forms no essential part of this invention. The forging *d* has surfaces at *g* and *h* which are intended to rest under the rail heads and upon the 85 rail bases or feet respectively, and it has two projections *k* adapted to pass through slots cut through the rail webs *c*, as shown at *l*, Fig. 1, and as seen in section in Fig. 2. The projections *k* are shaped so as to rest on the 90 foot portion *b* of the rails, as seen at *m* in Figs. 2 and 3, and their upper surfaces are inwardly inclined as shown. A tapering key *n* is adapted to be driven into the gap 95 between the top of the projections *k* and the underside of the rail heads *a*, in order to lock the same as shown. It will be apparent from Figs. 2 and 3 that the key *n* has a wedging action owing to the fact that the top surface of the projections *k* makes an 100 acute angle with the plane of the under-surface of the rail heads *a*. Hence the key as

it is driven in, tends to draw the projections *k* as far as possible through the slots at *l* in the rail webs, thus insuring effective contact at the surfaces *g*, *h* and *m*. The key 5 itself forms a support between the rail heads and the projections *k*, so that the rail heads are very effectively supported at the places where the slots *l* are formed in the web. The upper surfaces of the projections 10 *k* are tapered also longitudinally, so that the taper key *n*, as it is driven in from the left-hand side in Fig. 1, will wedge up more and more tightly between the projections *k* and the rail heads *a*. The taper is slight and 15 can scarcely be seen in the drawing. In practice it may be even less than is shown in the drawing. When the key *n* has been driven in tightly, its pointed end is bent over as seen at *o* in Fig. 1, in order to prevent loosening thereof, due for instance to 20 movement between the parts when the rails expand and contract. The slots at *l* are made long enough to allow for such expansion and contraction, and the gap between the rail ends is also sufficient for this purpose. 25 The fishplate may have strengthening ribs formed on it between the head and base at intervals, as indicated at *p* in Figs. 2 and 3, and in dotted lines in Fig. 1.

As applied to girders of I-section, the 30 joint may be made substantially like that for railway rails, but there is no necessity for a projecting head portion. Figs. 4 and 5 show a suitable construction, the parts being lettered to correspond with Figs. 1, 35 2 and 3. The girder ends are shown in Fig. 4 as abutting closely one against another.

In each case the method of fitting the 40 parts together is as follows. The rail or girder ends are placed so as to butt together or at the desired distance apart at their ends. The fishplate or forging is then applied to the outer side of the rails, or to either face of the girders, and it is tilted 45 to the extent required to permit the projecting portions *k* to be passed through the slots at *l* in both rails or girders, and then to lie upon the bases or feet of the rails or girders at the far side. In the rail joint, 50 when the parts are drawn up by the key *n*, the fishplate does not press against the rail webs, but is hollowed out as is usual on the inner face so as to make sure that the bearing surfaces are on the rail heads and bases. 55 In the girder joint however, this is not necessary; in the construction according to Fig. 5 the fishplate must tilt somewhat in going into position, and the head of the fishplate is cut down as is necessary

in order to enable it to pass under the 60 girder heads in all positions during insertion and removal.

Having thus described our invention what we claim as new and desire to secure by Letters Patent is:—

1. In a fish joint the combination with slotted rails or girders to be joined, of a fishplate with a plurality of projections thereon adapted to pass through the slots in the webs of said rails, and to rest on the 70 bases of the rails on the farther side thereof, and of a taper key member adapted to be inserted between the tops of said projections and the undersides of the top flanges of said rails, and to act as a wedge between the 75 same, pressing the bottoms of said projections upon the rail bases, and drawing said fishplate tightly against the rail faces at the other side of the web.

2. A fish joint device comprising a fish- 80 plate with a plurality of projections thereon each adapted to pass through a slot in the web of one of the elements to be joined, said fishplate having head and base portions adapted to bear internally against the 85 head and base portions of the elements to be joined, and said projections having base portions adapted to rest upon the bases of the elements to be joined beyond the webs thereof, and a taper key of wedge-shaped 90 section adapted to interlock between the heads of said projections and the heads of the elements to be joined.

3. In a fish joint for rails, the combination with the two rail ends to be joined, 95 each having a slot in its web portion, of a fishplate having two projections adapted to pass through said slots, said fishplate having head and base portions adapted to bear against the heads and bases of said 100 rail ends internally, and an extension lying above the rail heads at the joint, and said projections having foot portions adapted to rest on the rail bases beyond the webs, while their top surfaces form together with the 105 under sides of the rail heads a wedge-shaped groove, and of a tapered and wedge-shaped key member adapted to fit between the tops of said projections and the rail heads, and to draw the bearing surfaces between the fishplates and their projections 110 into close contact simultaneously with the rail heads and rail bases.

In witness whereof, we have hereunto signed our names this 1st day of December, 1916.

ALFRED JAMES JOHNSEN.
HENRY E. JOHNSEN.
